Primary Examiner — Cynthia R Underwood

(57) **CLAIM**

The ornamental design for a hook, as shown and described.

DESCRIPTION

FIG. 1 is a front, right side, top perspective view of a first embodiment of a hook, showing my new design;
FIG. 2 is a rear, left side, bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof; and,
FIG. 9 is another perspective view thereof, shown in an alternative position.
The broken lines in the figures illustrate portions of the hook that form no part of the claimed design.

1 Claim, 9 Drawing Sheets
